UNITED STATES PATENT OFFICE

LORETTA C. DOYLE, OF HOOSICK FALLS, NEW YORK, ASSIGNOR TO SPECIALTY INSULATION MANUFACTURING CO., INC., OF HOOSICK FALLS, NEW YORK, A CORPORATION

WORK STAND

Application filed January 3, 1931. Serial No. 506,369.

This invention relates generally to work stands and has particular reference to stands known as sewing stands for holding materials for use in sewing, such as thread, 5 needles, buttons, thimbles and so forth.

One object of this invention is the provision of a device of the character specified which is portable and formed of material molded into shape whereby the stand is substantially a unitary structure.

Another object of this invention is the provision of a device of the character described in which means are provided for holding needles in a concealed compartment.

A further object of this invention is the provision of a sewing stand having a handle which forms a chamber for receiving needles.

A still further object of this invention is the provision of a sewing stand having a two part handle, one of which parts provides a chamber for retaining needles and the other part forms a closure for said chamber and also a holder for an abrasive substance.

The invention further contemplates a construction which is easy and inexpensive to manufacture and strong and durable in operation.

Other objects and advantages of this invention will be apparent from the following description, taken in conjunction with the accompanying drawings, in which:

Figure 1 is a top plan view of the device.

Fig. 2 is a sectional view on the line 2—2, Fig. 1, and

Fig. 3 is a sectional view on the line 3—3, Fig. 2.

Referring now more particularly to the drawings in which similar characters of reference designate similar parts in the several views, A designates generally the base of the sewing stand and B indicates the handle.

The base A comprises a top portion 2 having a downwardly extending peripheral flange 4 provided at suitable intervals with enlarged portions 6 to which are secured in any suitable manner, the pads 8; the enlarged portions forming, in effect, internal, integral legs as will be obvious. The device is preferably molded of any suitable moldable material, such, for example as that

known in the art as "Colasta" but obviously may be formed of any suitable material.

The base A is provided with a substantially centrally arranged projection 10, forming one portion of the handle B and surrounding the projection is an annular recess 12; the recess forming a pocket for receiving buttons or other articles. The recess 12 is really formed in the top 2, as will be apparent from the drawings, and is provided with several upstanding hollow studs 14 forming supports for thimbles, and the annular rim 15 of top 2 is provided with upstanding pins 16 having shoulders 18 embedded in the material of said rim; the pins 16 being secured in position during molding of the base, and the under surface of said rim having integral bosses 17 in which the lower ends of said pins are arranged.

As before mentioned, the handle B is in two parts, the lower part being indicated at 10. Said portion 10 has its lower end cored out to define a chamber 20 in which is arranged a tray 22, having a stem 24 which extends upwardly through the projection 10 and beyond the latter. Secured to the upper end of the stem 24 is a knob 25. The stem extends through a central opening 26 formed in the projection 10 and is longitudinally movable therein to raise and lower the tray, the latter being adapted to support needles which are arranged in openings 28 formed in said projection 10. It will be obvious that when the tray is lifted the needles are brought into a position where they may be easily removed as desired.

The handle includes portion 30 which is removably secured to projection 10 by being threaded thereto and said portion 30 comprises a cap to cover the needles in the openings 28. The portion 30, or cap, is preferably hollow and is provided with a partition 32 intermediate its top and bottom edges to define a chamber 34 for holding a suitable abrasive material. In the instance shown, the portion 30 is formed of two parts, including a cover 36 threaded to the upper end of portion 30. In this instance, the upper end of cap 30 is reduced in thickness to define an annular shoulder 38 which

may be utilized to support a piece of material to be held in place by the cover 36 and through which needles may be passed into the abrasive material in chamber 34; the cover 36 being provided with an opening 40.

From the above description it is believed that the construction of the present invention will be fully apparent to those skilled in the art without further elaboration. The 10 device of the present invention is a unitary structure formed of moldable material, or to be more exact, the device is a molded construction having few parts but which possesses great utility and attractiveness.

15 The drawings herein illustrate one embodiment of the invention, but it is to be understood that they are for illustrative purposes only and that various changes in the form and proportions of the device may be 20 made within the scope of the appended claims without departing from the spirit of the invention.

What is claimed is:

1. A work stand of the kind described comprising a base having a central projection defining a handle portion, longitudinally shiftable means in the projection for supporting needles, and a second handle portion removably secured to the projection for concealing 25 the needles.

2. A work stand of the kind described comprising a base having a central projection defining a handle portion, longitudinally shiftable means in the projection for supporting needles, and a second handle portion removably secured to the projection for concealing 30 the needles, said second handle portion having a chamber formed therein for receiving an abrasive material.

3. In a work stand of the kind described, a base comprising a top having a depending peripheral supporting flange and a central projection, an annular recess surrounding the projection and provided with upstanding 45 studs, said projection having a hollow lower end, a tray longitudinally movable in said lower end and having a stem extending through the projection, the projection further having longitudinal apertures therethrough 50 for receiving needles to be supported and lifted by said tray, a cap secured to the projection, and a plurality of upstanding pins secured to the top of said base.

4. In a work stand of the kind described, a base having a projection the lower end of which is hollow to provide a tray receiving chamber, a tray supported by said projection in said chamber and longitudinally movable therein, said projection having a plurality of 55 longitudinal openings therethrough to receive needles to be supported on said tray, a hollow cap removably secured to the projection and a partition in said cap to define an abrasive receiving chamber.

65 5. In a work support of the kind described,

a hollow base member provided with a central projection and an annular recess therearound, said base and projection being formed as a unit of material molded to shape and having a plurality of upstanding pins secured to the 70 base adjacent the edge thereof, a plurality of upstanding hollow article supports arranged in the recess, a needle supporting tray carried by the projection and concealed therein, a hollow handle part removably secured to the 75 upper end of the projection, a partition in said hollow handle part defining an abrasive receiving chamber, and a lid removably secured to the upper end of said hollow handle part.

6. In a work support of the kind described, a base having a centrally arranged projection surrounded by an annular depression, a stud extending into the depression and formed integral with the base, said projection defining one part of a handle and being provided with a bottom recess and a plurality of longitudinally arranged openings for receiving needles, a tray movable in said recess adapted to support the needles in said openings, said tray 80 having a stem extending through and supported by said projection, and a cover secured to the upper end of said projection and forming the remainder of the handle.

7. In a work stand of the kind described, a base having an upstanding projection provided with needle receiving apertures, a tray supported by the projection and adapted to support needles arranged in the apertures, said tray being longitudinally shiftable in 100 the projection, and a closure member detachable secured to the projection for normally concealing the needles, the projection and closure member providing a handle for the work stand.

In witness whereof I have hereunto set my hand.

LORETTA C. DOYLE.
